UNITED STATES PATENT OFFICE.

HENRY JOSEPH IRWIN, OF JERSEY CITY, NEW JERSEY.

CARBONATOR.

Application filed April 2, 1923. Serial No. 629,271.

To all whom it may concern:

Be it known that I, HENRY J. IRWIN, a citizen of the United States, and resident of Jersey City, in the county of Hudson and 5 State of New Jersey, have invented certain new and useful Improvements in Carbonators, of which the following is a specification.

The invention relates to improvements in 10 carbonators of the class commonly used by bottlers for charging mineral waters, beverages and the like with carbonic acid gas under pressure, the liquid and gas being supplied to a carbonating tank, wherein 15 they are agitated and intimately mixed together, and then drawn off therefrom in a substantially continuous manner.

Heretofore the pump used for supplying 20 the liquid to the tank and the mixer or agitator have been driven independently of each other by a plurality of belts leading from a countershaft and arranged to rotate the agitator continuously while the pump is operated intermittently in accordance 25 with the amount of liquid drawn off.

One of the objects of the present invention is to provide a base on which the several parts of the carbonator together with the source of power may be mounted and 30 thus overcome the danger from the moving belts and economize in the operating space required.

A further object is to simplify the construction of the carbonator by providing 35 means operated by a single belt to drive both the pump and agitator independently of the other in order that the former may be operated intermittently while the latter is rotated continuously:

40 The invention also includes a clutch device for detachably connecting the driving means to the agitator in order that the latter may be either rotated or stopped to vary the quantity of gas applied to the liquid.

45 A further object includes means for operating a relief valve for removing the air which accumulates above the liquid within the tank and interferes with the efficient carbonation thereof.

50 For further comprehension of the inven-

tion, and of the objects and advantages thereof, reference is had to the following description and accompanying drawings, and to the appended claims in which the various features of the invention are more particularly pointed out.

55 Figure 1 of the drawings is a plan view showing an assembly of the several parts of the carbonating device as embodied in the present invention.

Figure 2 is a corresponding side elevation.

Figure 3, an end elevation, shown from the driving or pump end of the carbonator.

60 Figures 4 and 5 are respectively sectional and side views of a clutch coupling for the agitator shaft shown in enlarged detail.

65 Figures 6 ad 7 are respectively enlarged detail views showing plan and side views of an air valve and manner of operation.

70 In the drawings, numeral 1 designates the base or frame of the carbonator; carrying the legs 2 on which is supported the carbonating tank 3, provided with the usual valve controlled gas inlet 4 and the liquid supply pipe 5 leading from the pump 6. Also the tank is provided with flexible tubular connections 7 and 8 leading respectively from the top and bottom of the tank 75 to the float 9 and so arranged as to permit the liquid in the tank to freely flow into the float and maintain a common level therein.

75 Mounted upon the tank 3 is a bracket 10 having a hub 11 provided with a pin 12 arranged to pivotally support the double armed lever 13, the upper arm thereof being fixedly connected to a cross bar 14, one end of the latter being pivotally connected to the float 9, while along the opposite end of the bar a counter weight 15 is lengthwise adjustable to effect the regulation of movement of the float. At its lower end the bracket 10 is provided with a guide plate 16 arranged to slidably receive the lower 80 arm of the lever 13, the terminal thereof being pivotally secured to one end of a link rod 17, the opposite end being pivoted to an arm 18, fixed upon a rock-shaft 19 mounted in the bracket bearing 20, fixed to the upper 85 extension 21 of the base 1, corresponding extension 22 being formed on the base ex-

tension 21, and which together with the bracket bearing 20 are adapted to rotatably receive the driving shaft 23.

For the rotation of the driving shaft an electric motor 24 is provided and secured upon the base extension 21, and from which position the motor is adapted to serve as a source of power for operating the several parts of the carbonator from the motor-pulley 25 through the single bolt 26 to the pulleys 27 and 28, carried by the driving shaft 23, the former pulley 27 being fixed upon the shaft while the latter is loosely mounted thereon by the bush 29, a sprocket wheel 30 being fixed to the bush and arranged to transmit motion through the chain 31 to the larger sprocket wheel 32, the latter being detachably coupled to the agitator shaft 33. The agitator shaft extends through the tank, being mounted in the usual manner and provided with conventional blades 34, shown in dotted lines, and adapted to intermingle or mix the liquid and gas together.

As indicated in Fig. 1 the driving belt 26 is positioned to transmit motion through the loose pulley 28, sprocket 30, chain 31 and sprocket 32 to rotate the agitator. In this position the belt is free from the fast pulley 27 and the shaft 23 will remain inoperative. When the belt is positioned as shown in Fig. 2, the fast pulley 27 is fully engaged thereby and the loose pulley 28 only partially engaged, and in this position the belt will operate both the agitator shaft 33 and the driving shaft 23, the latter shaft being provided with a pinion 35 disposed to engage a relatively large gear 36 fixed upon a shaft 37, journaled in bearings 38, formed on the base extension 21. A crank-disc 39 is fixed to the outer end of shaft 37 and is provided with a crank-pin 40, carrying one end of a connection rod 41, the opposite end being pivotally mounted in a slide bar 42, mounted for movement in a boss 43, fixed to the base 21. A pump rod 43^a is fixed at its upper end to the slide bar 42, and at its lower end the rod is connected to a pump plunger slidable within the pump casing 6, the latter being provided with the usual outside pipe fittings and check valves to receive the liquid to be carbonated at the inlet portion 44 and feed it through the outlet connection 45 to the supply pipe 5. As thus geared it will be obvious that the pump will be operated during the rotation of the driving shaft 23 and that the latter may be stopped or started by shifting the belt into the two positions indicated in Figs. 1 and 2, the shifting movement of the belt being effected by a belt fork 46, fixed to the rock-shaft 19.

During the substantially continuous operation of drawing the carbonated liquid from the tank for bottling purposes, the level of

the carbonated liquid in the tank is gradually lowered until a corresponding low level in the float 9 causes the latter to be overbalanced by the counter weight 15, whereupon the parts will assume the position indicated in Figure 2 and the pump will be operated until a new supply of liquid is introduced into the tank and causes the level to gradually rise until the weight thereof within the float will overbalance the counter-weight and operate the lever 13, the rod 17, arm, 18, rock-shaft 19 and cause the belt fork 46 to shift the belt into the position indicated in Fig. 1, in which the pump is stopped while the agitator continues its mixing operation upon the solution within the tank. It will thus appear that periods of time will be required in which the pump will be in motion and in which the same will be at rest, and that these periods will correspond in the operating float lever 13, the lower end of which is provided with a cam 47.

Mounted adjacent the cam is a valve body 48 having a foot 49 arranged to be fixed upon one of the legs 2 which carry the carbonator tank. The valve may be preferably of the ordinary plug type, having an inlet at 50 and an escape outlet at 51, the plug or rotating member being provided with an arm 52, carrying at its free end a roller 53 arranged to engage the cam 47, the roller being normally held in contact therewith by the coil spring 54, one end of the latter engaging the arm 52 while the opposite end is fixed to the body of the valve. In the reciprocating movement of the cam as effected by the motion of the float arm 13, the arm 52 will be operated to quickly open and close the valve by the rotation of the plug therein, ports in the latter being suitably arranged to register with the outlet and inlet passages of the valve body, the latter passage 50 having a tubular connection 55 leading from the interior upper portion of the tank. The valve-operating cam 47 is shaped with a central high operating portion so that at opposite ends of each stroke the valve remains closed and is opened only during a brief period or the central portion of the cam's movement, sufficient only to permit the removal of the air ordinarily collecting in the upper portion of the carbonating tank above the relatively heavier carbonating gas.

In the regular carbonating operation it is frequently required that the liquid be variably charged with gas. For the maximum charge the agitator is rotated continuously, the blades thereof effecting a spraying action of the liquid within the tank which thoroughly intermingles with the gas, this condition being maintained during the bottling process. For effecting a semi or less gaseous charge of the liquid, the agitator

shaft 33 is stopped by the disconnection of the clutch secured to the end thereof, and under which condition the gas inlet valve 4 is adjusted to supply the amount of gas for 5 the required degree of carbonation.

As shown in detail in Figs. 4 and 5, the driving clutch for the agitator shaft 33 comprises a flanged sleeve or bush 56 inserted within the hub of the sprocket-wheel 32 and mounted upon the end of the agitator shaft, a collar 57 being disposed upon the bush in spaced relation to its flange and held thereon by a series of set-screws 58 which pass through the collar and bush and 10 fix the same to the shaft. Upon the bush between the flange thereof and the collar 57 is loosely mounted the sprocket-wheel 32, provided with a perforation to receive the drive-pin 59, the latter being loosely 15 mounted in a boss 60 formed on the collar 57. The drive pin 59 is provided with a reduced portion or stem 61, the latter having a laterally projecting stop-pin 62, adapted 20 to engage slots 63 formed in the outer end of the boss 60, the latter being correspondingly bored to slidably receive the variable 25 diameters of the drive-pin 59 and its reduced stem 61, the variation in bore of the hub forming a shoulder adapted to engage 30 one end of a helical spring 64, loosely mounted both within the boss and upon the stem and adapted at its opposite end to engage the shoulder formed by the drive stem and its reduced stem portion. A finger-grip 65 is fixed to the outer end of the stem 61 and by means of which the drive-pin 59 35 may be operated. As shown in the sectional view Fig. 4, the drive-pin engages the perforation in the sprocket wheel 32, and when 40 desired to disconnect the same and prevent rotation of the agitator-shaft 33, the finger-grip 65 is operated to withdraw the drive-pin from the wheel against the action of the spring 64 and turn the pin about its axis 45 and allow the projecting stop pin 62 to rest upon the outer end of the boss 60, in which 50 position the drive-pin will be held in detached relation with respect to the sprocket wheel by the tension of the spring. With 55 the clutch as thus constructed it will be evident that, upon the stoppage of the machine, the agitator shaft 33 may be quickly coupled or uncoupled to its drive wheel 32 for effecting the desired degree of carbonation of the liquid within the tank.

It is to be understood that the usual mountings including the necessary gauges, safety appliances and connections are to be applied to the tank in the usual manner.

Having thus described my invention and the manner in which the several devices co-operate with one another, what I claim as my invention and desire to secure by Letters Patent, is:

1. In a carbonating tank, an agitator, a

pump, means including a single driving belt for jointly operating said agitator and pump, and means for shifting said belt to intercept the movement of the pump while the agitator continues its operation.

70

2. In a carbonating tank, an agitator, a pump, means including a single driving belt for jointly operating said agitator and pump, and automatic means for shifting said belt to intercept the movement of the pump while the agitator continues its operation, said belt shifting means being operated by the change in level of the liquid within the tank.

75

3. In a carbonating tank, an agitator, a pump, means including a single driving belt for jointly operating said agitator and pump, and means for shifting said belt to start and stop said pump during the continued operation of the agitator, said shifting means being operated by the change in level of the liquid within the tank.

80

4. In a carbonating tank, an agitator, a pump, joint means for operating said agitator and pump, and means for starting and stopping said pump during the continued operation of the agitator, said operating means being controlled by the change in level of the liquid within the tank.

90

5. In a carbonating tank, a base therefor, an agitator for the tank, a pump carried by said base and arranged to supply liquid to the tank, a source of power carried by said base and arranged to jointly operate said agitator and pump, and means for starting and stopping said pump during the continued operation of the agitator, said means being controlled by the change in level of the liquid within the tank.

95

6. In a carbonating tank, an agitator, a pump, means for jointly operating said agitator and pump, means for starting and stopping said pump during the continued operation of the agitator, and means for arresting the movement of the agitator during the operation of the pump.

105

7. In a carbonating tank, an agitator, a pump, means including a single driving belt for jointly operating said agitator and pump, means for shifting said belt to intercept the movement of the pump while the agitator continues its operation, and means for intercepting the movement of the agitator while the pump continues its operation.

115

8. In a carbonating tank, an agitator, a pump, a driving shaft operatively geared to said pump, a driving pulley fixed upon said shaft, a second driving pulley loosely mounted on said driving shaft and operatively geared to said agitator, the face of the latter or second pulley being wider than that of the first mentioned pulley, a driving belt adapted to engage the two pulleys and having a width corresponding with that of the wider faced pulley, means for shifting

120

125

130

the belt to fully engage the wide face pulley to arrest the rotation of said driving shaft and pump and effect the rotation of the agitator, and means for shifting said belt to engage both of said pulleys for the rotation of both the agitator and the pump.

9. In a carbonating tank, means including a power shaft for supplying liquid thereto, an agitator for the liquid arranged

to be driven from said power shaft, and a clutch disposed to detachably connect the driving arrangement of said agitator while the liquid supply means remains connected to said power shaft.

Signed at New York, in the county of 15
New York and State of New York, this 31st
day of March, A. D. 1923.

HENRY JOSEPH IRWIN.
